UNITED STATES PATENT OFFICE.

ALBERT HUBBELL, OF RAVENWOOD, MISSOURI.

STRAW-SPREADER.

1,163,013.

Specification of Letters Patent. Patented Dec. 7, 1915.

Application filed December 2, 1914. Serial No. 875,143.

To all whom it may concern:

Be it known that I, ALBERT HUBBELL, a citizen of the United States, residing at Ravenwood, in the county of Nodaway and State of Missouri, have invented certain new and useful Improvements in Straw-Spreaders, of which the following is a specification, reference being had to the accompanying drawings.

This invention relates to certain improvements in straw spreaders and has relation more particularly to a device of this general character especially designed and adapted for use for the spreading of straw or the like; and an object of the invention is to provide a spreader of this general character having novel and improved means whereby a maximum of efficiency may be attained.

It is also an object of the invention to provide a device of this general character having novel and improved means whereby the straw to be distributed is delivered upon a broadcast mechanism whereby the straw is thrown over an increased area.

The invention also contemplates for an object the provision of a device of this general character having novel and improved means whereby any grain held by the straw to be distributed may be collected with convenience and facility.

Furthermore, the invention has for an object to provide a device of this general character having novel and improved means whereby the straw is automatically delivered to a feeding mechanism and whereby such delivery of the straw may be regulated with convenience.

The invention consists in the details of construction and in the combination and arrangement of the several parts of my improved straw spreader whereby certain important advantages are attained and the device is rendered simpler, less expensive and otherwise more convenient and advantageous for use, all as will be hereinafter more fully set forth.

The novel features of the invention will be carefully defined in the appended claims.

In order that my invention may be better understood, I will now proceed to describe the same with reference to the accompanying drawings, wherein—

Figure 1 is a side elevational view of a straw spreader constructed in accordance with an embodiment of my invention; Fig.

2 is a top plan view of the device as disclosed in Fig. 1; Fig. 3 is a sectional view taken substantially on the line 3—3 of Fig. 2; Fig. 4 is a sectional view taken substantially on the line 4—4 of Fig. 1, with certain of the parts omitted; Fig. 5 is a rear elevational view of the device as herein disclosed; Fig. 6 is a sectional view taken substantially on the line 6—6 of Fig. 2; Fig. 7 is a sectional view taken substantially on the line 7—7 of Fig. 2; Fig. 8 is a fragmentary view, partly in side elevation and partly in section, illustrating the elevating mechanism, herein embodied, in detail; Fig. 9 is a view, partly in elevation and partly in section, illustrating in detail the operative connection with the drive chain coacting with a rear supporting wheel; Fig. 10 is a fragmentary view in cross section and on an enlarged scale of the delivery mechanism as herein embodied; Fig. 11 is a fragmentary view, partly in elevation and partly in longitudinal section, of a portion of the delivery mechanism as herein embodied; and Fig. 12 is a view in perspective, detached, of a bearing member herein embodied.

As disclosed in the accompanying drawings, 1 denotes a frame of predetermined dimensions and preferably of rectangular form having disposed transversely of its rear extremity the axle 2 on the projected extremities of which are mounted the supporting wheels 3 while the forward portion of said frame is operatively supported by a steering truck 4 of conventional construction and with which is adapted to coact any desired arrangement of draft rigging, generally indicated at 5.

The longitudinal sides 6 of the frame 1 are of such a height as to afford a substantially box-like structure while the opposite extremities of such side members are tied or connected by the sills 7. Disposed across the top of the frame 1 and directed longitudinally thereof are the spaced rods 8, the extremities whereof being disposed through the sills 7 and engaged by the nuts or burs 8' whereby it will be readily perceived that the rods 8 are effectively maintained in operative position.

The side members 6 and the forward extremity of the frame 1 are provided with the copings 9 to which are suitably secured the racks 10 of any desired construction and which are adapted to afford a basket or hop-

per into which the straw, to be distributed, is initially deposited.

Adjacent the rear extremity of the frame 1 and in close proximity to the upper marginal portions of the side members 6 is disposed the transverse shaft 11 mounted in the bearings 12 disposed through the side members 6, said shaft 11 projecting beyond opposite sides of the frame 1, for a purpose 10 which will hereinafter be more particularly referred to.

The bearings 12, hereinbefore referred to, project inwardly of the frame 1 and serve as mountings for the side bars 14 of the delivery mechanism D. The opposite extremities of the side bars 14 are provided with the depending racks 15 in mesh with the gears 16 suitably affixed to the shaft 17 disposed transversely of the frame 1 adjacent its forward end and operatively supported by the side members 6 thereof. At a predetermined point intermediate its length, the shaft 17 is provided with a worm gear 18 in mesh with a worm 19 produced on the 25 vertically disposed shaft 20 terminating in close proximity to the seat structure S and provided at its upper extremity with suitable means 21 whereby the shaft 20 may be rotated in either direction in order to adjust the positions of the side bars 14 of the delivery mechanism D relative to the spaced rods 8, hereinbefore referred to.

At predetermined points intermediate their lengths the side bars 14 are tied or 35 connected by the cross beams 22 adapted to support an imperforate floor 23 over which is adapted to travel the endless chains 24 directed around suitable sprockets 25 fixed to the shaft 11 and around the sprockets 26 40 fixed to the transverse shaft 27 operatively supported by the side bars 14 adjacent their free extremities. At regular intervals the chains 24 are connected by the transverse slats 28 having projecting from their outer 45 faces the tines 68 adapted to pass between adjacent rods 8 in order to convey or deliver the straw rearwardly of the machine. It will now, it is thought, be self-evident that the adjustment of the side bars 14 of 50 the delivery mechanism D will determine or regulate the delivery of the straw, for reasons which are believed to be apparent.

Adjacent their rear extremities the side members 6 of the frame 1 are provided with 55 the transversely disposed wall 29 having projecting therefrom at substantially midway its height, the horizontally disposed platform 30 through which are disposed the vertical shafts 31, the lower extremities 60 whereof being suitably supported in the bearings 32 on the supplemental platform 33 disposed below the platform 30, hereinbefore referred to, and suitably connected with the frame 1. Each of the shafts 31 65 above the platform 30 has radiating there-

from the arms 34 of predetermined length and which are adapted upon rotation of the shaft 31 to throw the straw broadcast.

Affixed to each of the shafts 31 at a point below the platform 30 is a beveled gear 35 70 in mesh with a similar gear 36 mounted on an extremity of a stub shaft 37 operatively supported by the platform 33. The stub shaft 37 has affixed thereto a sprocket 39 around which is disposed the sprocket 75 chain 40 also directed around a sprocket 41 fixed to the transverse shaft 42 operatively supported by the side walls 38 connecting the platforms 30 and 33, and projecting therebeyond.

To each projected portion of the shaft 42 80 is affixed a sprocket 43 around which is disposed a drive chain 44 also directed around an enlarged sprocket 45 loosely mounted on the axle 2, hereinbefore referred to, and 85 provided with a clutch member 46 adapted to coact with a second clutch member 47 carried by the adjacent wheel 3. The clutch members 46 and 47 are normally maintained in locking engagement through the medium 90 of the expandable member 48, herein disclosed as a conventional coil spring, surrounding the axle 2 and interposed between the hub of the sprocket and a stop 49 suitably positioned upon the axle.

In view of the foregoing, it will be readily perceived that with the clutch members 46 and 47 in locking engagement the shaft 31 will be caused to rotate upon the travel of the machine. In order, however, to maintain the shaft 31, or more particularly the sprockets 45, against rotation as desired, I provide in the hubs thereof the annular grooves 50 operatively engaged by the forks 51, the extremities of such forks being operatively connected through the medium of the flexible members 52 with the opposite extremities of the lever 53 pivotally engaged at substantially its longitudinal center, as indicated at 54, with the axle 2 whereby it will be readily perceived that upon rocking movement being imparted to the lever 53 in one direction, the clutch members 46 will be disengaged from the clutch members 47. Coacting with the flexible 105 members 52 are the guide rollers 55 carried by the axle 2 and whereby the movement of the forks under the influence of the lever is 110 materially facilitated.

Projecting laterally from the lever 53 at 120 its longitudinal center is an arm 56 having pivotally engaged with the extremity thereof the forwardly directed rod 57 also pivotally engaged with the lower extremity of the vertically disposed lever 58 terminating 125 in close proximity to the seat structure S and provided with a conventional spring latch 59 coacting with a rack 60 whereby it will be readily perceived that the occupant of the seat structure S may throw the 130

sprockets 45 into or out of clutch as desired.

Projecting upwardly from the rear sill 7 at the opposite ends thereof are the standards 61 and mounted in the upper extremities of such standards is the transverse shaft 62 having fixed thereon intermediate the standards the sprockets 63 around which are directed the chains 64 also disposed 10 around the sprockets 63 fixed to the shaft 62^a operatively supported by the lower extremities of the forwardly and downwardly inclined frame 66, as is believed to be clearly shown in the accompanying drawings, and 15 it is to be observed that such frame 66 terminates in close proximity to the rods 8. The chains 64 are connected by the transversely disposed slats 67 spaced one from the other a distance equal to the space between 20 the slats 28 and projecting from the outer faces of the slats 67 are the tines 69 which are adapted to engage the straw as delivered by the delivery mechanism D and to convey the same upwardly and discharge 25 the straw upon the broadcasting mechanism B, which has been hereinbefore referred to and of which the shafts constitute parts. It is to be observed that disposed above the chains 64 and their concomitant parts is a 30 hood or casing 70 of suitable configuration which serves to confine the straw being conveyed by the feeding mechanism F and to assure its proper discharge upon the broadcasting mechanism B.

35 The shaft 62^a projects beyond the opposite sides of the machine and to each of such projected portions is affixed a sprocket wheel 71 having disposed therearound a sprocket chain 72 also directed around a sprocket 73 fixed to a shaft 74 disposed transversely of the frame 1 adjacent its rear extremity and operatively supported by the side members 6 thereof. The chain 72 is also disposed around a sprocket 75 mounted on a projected extremity of the shaft 11, hereinbefore referred to. Also fixed to each projected extremity of the shaft 74 is a sprocket 76 operatively engaged by the adjacent drive chain 44. By this arrangement 45 it will be readily perceived that the delivery mechanism D, the feeding mechanism F and the broadcasting mechanism B are all operatively driven in unison and by the rear wheels 3.

50 It is to be observed that the sprocket wheels 71 and 73 are of a ratio of 1 to 2, whereby the chains 64 travel at a speed twice as fast as the speed of the chains 24 and the tines 69 are adapted to dip twice while 55 one slat 28 is approaching in order to assure the stripping of the straw from the tines 68 of said slat 28 just before the slat 28 turns. It is also to be observed that the tines 69 and 65 of the feeding mechanism pass between adjacent rods 8 other than the rods between which the tines 68 pass in order that such tines 68 and 69 will not interfere one with the other. In practice, I find it of particular advantage to have the tines 68 and 69 passing beyond opposite sides of common rods 8. It is also to be observed that the shafts 31 rotate in reverse directions whereby the straw may be distributed over a materially large area.

As the straw is being carried rearwardly by the delivery mechanism D, it will be readily perceived that the shattered grain within the straw will readily fall between the rods 8 upon the imperforate floor 23 and be carried rearwardly of the machine by the slats 28 and discharged through the comb 77 into the trough 78 disposed transversely of the frame 1 adjacent the rear thereof. As herein set forth, the comb 77 is operatively supported by the wall 29 and is of such a length as to extend entirely across the trough 78 so that any straw carried around the shaft 11 will be discharged upon the ground, it being observed that the comb 77 is so positioned as to permit the tines 68 passing between the teeth 79 of the comb 77.

The shaft 74, hereinbefore referred to, is disposed longitudinally of the trough 78 and has affixed thereto the spiral 80 which serves to convey the grain deposited within the trough transversely of the frame and to deliver the same within the lower extremity of the upwardly and forwardly disposed chute 81, the upper end whereof being open and adapted to discharge within the box 82 carried by one of the side members 6 of the frame 1, as is believed to be self-evident. The lower extremity of the chute 81 is intersected by the shaft 74 and to said shaft 74 within the chute 81 is affixed the sprocket wheel 83 around which is disposed the sprocket chain 84 also directed around a sprocket 85 fixed to a shaft 86 disposed transversely of the chute at its upper extremity and operatively supported by the side walls thereof, one extremity of said shaft 86 projecting beyond one side of the chute. The chain 84 is provided with the cups 87 which are adapted to force the collected grain upwardly of the chute so that the same may be discharged within the box 82.

The box 82 is so positioned relative to the discharge end of the chute 81 as to afford a space therebetween in order that an air blast may be employed for separating the chaff from the grain. As herein disclosed a fan casing 88 is carried by a side member 6 of the frame 1 immediately to the rear of the box 82 and having a spout 89 to properly direct the air blast and the fan blades 90 are mounted upon a shaft 91 projecting exteriorly of the casing. The projected portion of the shaft 91 is provided with a pulley

92 around which is disposed a belt 93 also directed around a pulley 94 affixed to the projected extremity of the shaft 86. It is to be observed that the pulley 94 is of materially greater diameter than the pulley 92, for reasons which are believed to be self-evident. I also find it of particular advantage to dispose rearwardly of each of the shafts 31 the vertically disposed and horizontally curved plate 95 which serves to assure a proper scattering of the straw, as is believed to be self-evident.

From the foregoing description, it is thought to be obvious that an agricultural machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

- 30 1. A device of the character described comprising a frame, parallel rods disposed along the upper face of the frame, a shaft disposed across the frame against one end thereof, side bars pivotally supported by the shaft, driven means for adjustably supporting the opposite ends of the side bars, a second shaft supported by the opposite end portions of the side bars, and an endless delivery means operatively engaged with the shafts, said means being adapted to be directed between the rods.
- 35 2. A device of the character described comprising a frame, parallel rods disposed along the upper face of the frame, a shaft

disposed across the frame adjacent one end 45 thereof, side bars pivotally supported by the shaft, racks depending from the free extremities of the bars, a shaft supported by the frame, gears carried by the shaft in mesh with the rack, means for axially rotating 50 the last named shaft, a shaft operatively supported in the free end portions of the side bars, and an endless delivery means operatively engaged with the first and last named shafts and provided with means 55 adapted to project between the rods of the frame.

3. A device of the character described comprising a frame, parallel rods disposed across the upper face of the frame, an imperforate floor disposed below the rods, a delivery means movable over the imperforate floor and adapted to project between the rods, a trough disposed transversely of the imperforate floor adjacent the discharge 65 end of the delivery means, and a comb interposed between the discharge end of the imperforate floor and the trough and overlying the same, said delivery means also projecting between the teeth of the comb. 70

4. A device of the character described comprising a frame, parallel rods intersecting the frame, side bars pivotally supported below the rods and capable of swinging movement toward and from said rods, a 75 contacting mechanism carried by said bars and projecting between the rods, a rack depending from one of the bars, and rotatable means operatively engaged with said rack for swinging the bars relative to the 80 rods.

In testimony whereof I hereunto affix my signature in the presence of two witnesses.

ALBERT HUBBELL.

Witnesses:
